US00D557262S

(12) **United States Design Patent** (10) Patent No.: **US D557,262 S**
Sakai (45) Date of Patent: **** Dec. 11, 2007**

(54) **COMBINED DISC PLAYER AND RADIO RECEIVER**

(75) Inventor: **Wakaba Sakai**, Tokyo (JP)

(73) Assignee: **Sony Corporation**, Tokyo (JP)

(**) Term: **14 Years**

(21) Appl. No.: **29/213,312**

(22) Filed: **Sep. 16, 2004**

(51) **LOC (8) Cl. 14-03**

(52) **U.S. Cl. D14/257**

(58) **Field of Classification Search** D14/257, D14/156, 160–165, 168–169, 192–198, 188, D14/445, 126; 360/99.02, 99.07; 369/75.11, 369/75.21

See application file for complete search history.
